UNITED STATES PATENT OFFICE.

HARRISON E. AKERS, OF TYLER, TEXAS.

GUARD-RAIL CLAMP.

Application filed April 29, 1926. Serial No. 105,578.

This invention relates to guard rail clamps and it is an object of the invention to provide means whereby a guard rail may be effectively maintained in applied position but in a manner whereby the guard rail may be readily adjusted with respect to the main rail as the occasions of practice may necessitate.

It is well known that guard rails, and especially those employed opposite to a frog, are subjected to excessive wear and when unduly worn there is a liability of a train jumping. The invention has for an object to provide means whereby the guard rail may be effectively anchored in applied position yet conveniently adjusted with respect to the main rail to maintain the standard spacing between said main rail and guard rail and which adjustment can be accomplished with a minimum of labor.

The invention consists in the details of construction and in the combination and arrangement of the several parts of my improved guard rail clamp whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan with a portion broken away illustrating guard rail clamps constructed in accordance with an embodiment of my invention and in applied position;

Figure 2 is a sectional view taken substantially on the line 2-2 of Figure 1;

Figure 3 is a sectional view taken substantially on the line 3-3 of Figure 1;

Figure 4 is a sectional view taken substantially on the line 4-4 of Figure 1;

Figure 5 is a view in bottom plan of one of the spreader blocks illustrated in the preceding figures;

Figure 6 is a fragmentary view in top plan illustrating a spreader block constructed in accordance with a further embodiment of my invention and in applied position;

Figure 7 is a sectional view taken substantially on the line 7-7 of Figure 6;

Figure 8 is a view in bottom plan of the

spreader block illustrated in Figure 6 unapplied.

As illustrated in the accompanying drawings, G denotes a guard rail located in the usual manner at proper position with respect to the main rail M to act on the inner side of the wheel flanges of rolling stock to prevent the flanges of the opposite wheels from mounting or taking the wrong side of a frog point and thus minimizing the liability of a train jumping. The guard rail G is of a conventional type and has its extremities outturned, as at 1.

The central portions of the rails M and G are rested on a base plate 2 arranged upon the upper surface of a tie T and coacting with said plate 2 are the rail plates 3 and 4 engageable with the outer base flanges of said rails. As is particularly illustrated in Figure 1, it is to be noted that the rail plate 4 is adapted to be adjusted in a direction lengthwise of the plate 2 in order to compensate for the adjustment of the rail G with respect to the rail M.

Coacting with each outturned portion 1 of the rail G and the adjacent portion of the main rail M is a clamp constructed in accordance with an embodiment of my invention and, as herein disclosed, such clamp

comprises a bar 5 which underlies the rails M and G and having close contact therewith from below. One end portion of the bar 5

is provided with the upwardly and inwardly extending hook member 6 which snugly receives an outer base flange of the guard rail G, the outer or free end portion of said hook member 6 being transversely inclined,

as at a to correspond with the inclination of the web of the coacting outturned portion 1 of the rail G, as is particularly illustrated in Figure 1. This end a when the bar is in applied position has close contact with such web.

The opposite end of the bar 5 is provided with the inwardly facing hook member 7 which, when the bar 5 is in applied position preferably terminates slightly outwardly of or beyond the base flange of the rail M. This structure of the bar 5 and the hook members 6 and 7 is such as to facilitate the ready application of the bar in working position. The inner or free end of the hook member 7 is also disposed transversely on an incline, as at b, said inclined edge being reversed to the inclined edge a.

A wedge member W is engaged between the rail M and the free end of the hook

member 7, the outer longitudinal margin *c* of the member 7 being disposed on an incline substantially complementary to the inclination of the end *b* of the hook member 7. The wedge member W is applied into working position through the outer side of the applied bar 5 and as it is forced inwardly the wedge assures effective clamping engagement with the rails M and G.

10 The outer or larger end of the wedge member W is provided with a laterally disposed and outstanding flange or extension 8 through which is freely disposed a bolt 9, said bolt being also freely insertible 15 through the hook member 7. After the wedge has been properly positioned a holding nut 10 is threaded upon the bolt 9 for coaction with the inner face of the hook member 7 to maintain the wedge member W in desired applied position. In practice, I find it of importance to interpose between the applied nut 10 and the hook member 7 a 20 spring washer 11 which provides means to compensate for expansion or contraction incident to temperature changes and also to 25 hold the applied nut 10 against backing off.

Before the bar 5 is placed in clamping engagement with the rails M and G, I insert 30 between the adjacent outturned portion 1 of the rail G and the main rail M a filler block B, a marginal portion 12 of which being inclined similar to the inclination of the outturned portion 1. The inner or restricted end of the block B has depending 35 therefrom a lug 14 which is adapted to abut the inner face of the applied bar 5 to hold the filler block B against outward movement. The coaction between the inclined side face 12 of the block B and the outturned portion 1 of the rail G holds the applied block B 40 against movement inwardly of the rail G.

As the rail G wears and it is found necessary to move or adjust said rail G with respect to the main rail M to maintain the 45 standard spacing, it is only necessary to release the wedges W and to sufficiently withdraw the filler block B and bars 5 to effect the requisite movement of the guard rail G toward the rail M. When the desired adjustment has been accomplished the bars 50 are then effectively held to the rails M and G upon forcing the wedge members W in desired working position. I also find it of advantage to have the outer face of each of 55 the wedge members W at its lower portion provided with an outstanding flange 15 to extend between the hook members 7 and the adjacent end portion of the bar 5 to provide effective means to prevent displacement of 60 an applied wedge member.

In the embodiment of my invention as illustrated in Figures 6, 7 and 8, each filler block B' has engaged therewith and preferably through the medium of a hook 16 an

end portion of an elongated bar or strip 17. The opposite end portion of this bar or strip 17 is adapted to overlie an adjacent tie T and is secured or anchored thereto by a conventional spike 18. The bar or strip 17 is provided therealong with the spaced openings 19 through one of which the spike 18 is adapted to be selectively disposed as the occasions of practice may prefer.

From the foregoing description it is thought to be obvious that a guard rail clamp constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with two rails arranged side by side, one of the rails having an end portion outturned, a filler block engaged between the outturned portion and the second rail, a bar underlying both of the rails and having inwardly facing hook members, one of said hook members having close contact with the base flange of one of the rails, a wedge member coacting with the second rail and the second hook member, means coacting with said second hook member and the wedge member for holding the wedge member against displacement, the outturned portion of the first rail holding the filler block against movement in one direction, and means for holding said filler block against movement in the opposite direction.

2. In combination with two rails arranged side by side, one of the rails having an end portion outturned, a filler block engaged between the outturned portion and the second rail, a bar underlying both of the rails and having inwardly facing hook members, one of said hook members having close contact with the base flange of one of the rails, a wedge member coacting with the second rail and the second hook member, means coacting with said second hook member and the wedge member for holding the wedge member against displacement, the outturned portion of the first rail holding the filler block against movement in one direction, and a lug depending from the filler block for contact with the bar for holding said filler block against movement in the opposite direction.

In testimony whereof I hereunto affix my signature.

HARRISON R. AKERS.
